UNITED STATES PATENT OFFICE.

HERBERT B. MOSES, OF WASHINGTON, DISTRICT OF COLUMBIA.

FIXATION OF NITROGEN.

No Drawing.

Application filed March 5, 1919. Serial No. 280,761.

To all whom it may concern:

Be it known that I, HERBERT B. MOSES, a citizen of the United States, residing at Washington, in the District of Columbia, have invented certain new and useful Improvements in the Fixation of Nitrogen, of which the following is a specification.

This invention relates to the fixation of nitrogen; and it comprises a method of fixing nitrogen wherein the liquid nitrogen of liquid air is utilized as a source of nitrogen, heat and chemical reaction being locally developed in, or in proximity to, a body of liquid comprising liquid nitrogen wherein the products of reaction are taken up, as in forming nitrogen oxids by the local production of high temperature in, or in proximity to, a body of liquid air; all as more fully hereinafter set forth and as claimed.

In the fixation of nitrogen as nitrogen oxids or as ammonia, it is usual to resort to high pressures to obtain a high concentration of nitrogen in the reaction space, or to use high temperatures to facilitate reaction. Sometimes both high pressure and high temperature are simultaneously used.

In the present invention I depart from this practice and obtain a high concentration of nitrogen by liquefying it. In liquid nitrogen the concentration of nitrogen is greater than can be obtained by any commercially practicable pressure exerted on the gas. The same is true of liquid air which contains around 80 per cent of nitrogen. In a liquid mixture of nitrogen and hydrogen, the concentration of nitrogen is greater than can be conveniently obtained by pressure alone.

Combination of gaseous oxygen and gaseous nitrogen takes place freely at high temperatures; but the products of oxidation tend to dissociate again; that is, in cooling down from these high temperatures to the ordinary temperature, the oxygen and nitrogen tend to revert to their elemental form. This is a well recognized fact in the various arc processes of producing nitrogen oxids; processes in which air is momentarily subjected to the high temperature of the arc. In these processes simple atmospheric cooling is generally relied upon for the desired rapid cooling of the arc products through the dangerous temperature ranges.

In one embodiment of the present invention I form oxidation products of nitrogen

by producing an intense heat locally within, or in near proximity to, a body of liquid air; the volume of liquid air being so great that as part of the liquid is used up, other liquid will flow towards the locus, area or zone of heat to take its place. In so doing, the products of oxidation formed at the high temperature are instantaneously chilled by the liquid air; passing swiftly through the dangerous range of temperatures mentioned. As long as such an action, that is, local high heating in the presence of liquid air, can be obtained, the precise ratio of volume of liquid air to that undergoing reaction is, of course, not essential; but it is commonly most convenient to use a relatively large volume of the liquid. The localized high temperature may be produced under, at or near the surface of the body of liquid air.

The source of heat used in the described process may be varied. For example, it may be an electric current passing through a suitable resistance body; this resistor being either a first or second class conductor. Or there may be employed an electric spark or an electric arc. Heat may be chemically developed by the oxidation, at the expense of part of the oxygen of the liquid air, of oxidizable or combustible material. On the whole, however, I find some type of electric heat most applicable, as it enables more convenient localization of the zone or locus of high temperatures. In using combustion heat, special precautions must be taken to avoid explosion.

The described method may also be conveniently used in the production of NH_3 from liquid mixtures of nitrogen and hydrogen.

Liquid air can be employed, but in this event some of the oxygen combines with the hydrogen and I regard it as better to use liquid nitrogen or nitrogen-rich liquids produced in the liquefaction of air.

What I claim is:—

1. The process of forming a normally gaseous nitrogen compound which comprises subjecting a liquid body consisting essentially of liquid nitrogen and a body capable of uniting with said nitrogen to form gaseous nitrogen compounds to a locus of high heat.

2. The process of forming normally gaseous nitrogen compounds which comprises subjecting a liquid body consisting essentially of liquid nitrogen and another element

capable of uniting with said nitrogen to form gaseous nitrogen compounds to a source of high heat.

3. The process of forming normally gaseous nitrogen compounds which comprises subjecting continuously a liquid body consisting essentially of liquid nitrogen and another element capable of uniting with said nitrogen to form gaseous nitrogen compounds to a source of high heat.

4. The process of forming nitrogen oxides which comprises subjecting a body of liquid consisting essentially of nitrogen and oxygen to a locus of high heat.

15 5. The process of forming nitrogen oxides which comprises subjecting continuously a body of liquid consisting essentially of nitrogen and oxygen to a locus of high heat.

6. The process of forming nitrogen oxides

which comprises contacting a liquid body 20 consisting essentially of liquid air with a locus of high heat.

7. The process of forming nitrogen oxides which comprises contacting a body of liquid consisting essentially of nitrogen and oxygen 25 with a source of high heat.

8. The process of forming nitrogen oxides which comprises contacting a liquid body consisting essentially of liquid air with a source of high heat.

9. The process of combining elemental nitrogen with another element to form a normally gaseous compound which comprises maintaining a source of high heat in contact with a liquid mixture consisting essentially 35 of nitrogen and the other element.

HERBERT B. MOSES.
